UNITED STATES PATENT OFFICE.

ROBERT E. BRESSLER, OF HAMMOND, INDIANA, ASSIGNOR TO O. F. JORDAN COMPANY, OF EAST CHICAGO, INDIANA, A CORPORATION OF INDIANA.

RAILROAD WAY-CONSTRUCTION AND MAINTENANCE CAR.

1,328,489.

Specification of Letters Patent. Patented Jan. 20, 1920.

Application filed September 3, 1918. Serial No. 252,398.

To all whom it may concern:

Be it known that I, ROBERT E. BRESSLER, a citizen of the United States, and a resident of Hammond, county of Lake, State of Indiana, have invented certain new and useful Improvements in Railroad Way-Construction and Maintenance Cars, of which the following is a specification.

My invention relates to improvements in machines for constructing and maintaining railroads and has particular reference to improvements in ballast shaping and ditching cars.

The general object of my invention is to provide means wherewith the material, collected in ballast shaping, ditching or otherwise, can be carried along with the car through deep cuts and wasted over the bank at the end of the cut, or in the event the cut be a long one, left in spaced piles in the cut for convenient removal thereafter.

Another object of my invention is to provide a ballast shaping and ditching car wherewith the road can be simultaneously shaped and ditched, the excess material from the ditch and elsewhere on the ballast shaping wing being carried along with the car, and if the cut be a relatively short one wasted over the back at the end of the cut, or if the cut be a long one left in spaced piles within the cut for convenient removal.

A further object of my invention is to provide a ditching attachment that can be employed in conjunction with railroad spreaders of types in current use.

A further object of my invention is to provide material conveying mechanism that can be employed in conjunction with the ballast shaping wing or spreader wing of such form and construction as to be automatically moved from inoperative to operative position and vice-versa through the mere movements of the ballast shaping, spreader, or side wing as the case may be.

My invention consists generally in the form, construction, arrangement and coöperation of the parts, whereby the above named objects, together with others which will appear hereinafter, are attainable; and my invention will be more readily under-

stood by reference to the accompanying drawings which illustrate the preferred embodiment thereof.

In said drawings Figure 1, is a plan view of a railroad car embodying my invention; Fig. 2 is a side elevation of the car shown in Fig. 1; and Fig. 3 is a fragmentary detailed view substantially on the line 3—3 of Fig. 2, certain of the structure being broken away better to disclose the bracing members.

In the drawings, I have shown my invention as combined with or as a part of a railroad spreader car of the well-known Jordan construction such as is disclosed by O. F. Jordan Patent No. 996,256 of June 27, 1911. It should be distinctly understood however that this car is used for illustrating purposes, and that except where limited by the claims, I may employ a car of any suitable construction. While it is not necessary to describe the car in detail, since such description will be found in said patent, nevertheless a general description of the car and its operation will be helpful. I might add that my invention as here embodied is applied to the standard Jordan spreader, the spreader wings, marked 12 in said patent, and some of the braces, thereof having been removed. The car is provided with the front and rear trucks 1 and 2 and with suitable center and side sills. At a point just back of the front trucks will be found vertical columns 6—6 which are secured to opposite sides of the under frames and which extend nearly to the rails. The ballast shaping wing 12^a is operated in the same manner and by the same mechanism by which the spreader wing 12 of the standard Jordan spreader is operated. The ballast shaping wing 12^a is attached at one end to the movable hinge posts 9—9 which are freely slideable in the column 6. These posts are operated by means of compressed air engines 10, 10 and the car is equipped with a compressed air reservoir 10^a suitably connected to the engines 10, 10. I have not here detailed the pipe connections and valves since they may be as shown in the hereinbefore mentioned Jordan patent.

The two sides of the car are exactly alike except that the parts occupy reverse positions; this being the case a description of one side, and its operating mechanism, will 5 serve clearly to define both sides. It should be here remarked that the mechanism on each side is independently operated and that either one thereof or both may be used at one time according to the work to be done.

- 10 The post 9 bears a heavy hinge plate 9" on its lower part and to this is secured the heavy hinge section 11^a. The pivot pin of the hinge occupies a vertical position and the wing 12^a is pivoted in the part 11^a by 15 means of the horizontal pin 13. The two pivot pins being at right angles, allow the wing 12^a to swing in both horizontal and vertical directions. The horizontal movement occurs in distending and retracting 20 the wing to and from its working position and the vertical movement when it is desired to incline the same to any desired angle to the horizontal plane in the ballast shaping of the road bed. The free end of 25 the wing 12^a is sustained and also braced by an adjustable telescopic brace member 14^a, the lower end of which is pivotally attached to the wing at 14^a, and the upper end of which is vertically pivoted at 14^a' 30 to a plate 9'" upon the upper part of the post 9. The wing 12^a being attached to the post obviously rises and falls with the post. The wing 12^a is shown in distended or operative position on the near side of the car in 35 Fig. 1 and in closed or inoperative position on the far side.

For holding the wing distended against the ballast, which it must displace as the car is moved forward, I prefer to employ 40 a plurality of braces *a—a* which extend from the side of the car to the inner side of the wing and which are constructed and operated in the manner of the braces *a—a* in said Patent No. 996,256. It is not thought 45 necessary to describe these in detail and it will be only said these braces *a—a* serve both as braces and as toggle members whereby when the shaft 18 is rocked, as by means of an air engine 19, they serve to throw or move 50 the wing 12^a outwardly to operative position or inwardly to inoperative position.

When it is desired to form a ditch D on the side of the road bed the wing 12^a is of a form having a portion 12^a which is given 55 that shape desired in the completed ditch. In railroad practice it is necessary even after the ditch is originally formed to clear it several times during the year if the road bed is to be maintained in proper order. 60 Whether the ballast shaping and ditching portion 12^a be used in the initial construction work or in maintenance work a quantity of material indicated at M in the drawings will pile up forward of the wing 12^a.

In passing through a cut this would soon 65 waste over the end of the wing 12^a and into the preformed ditch thus making impossible the formation of a proper ditch. To prevent any such action, I provide what I term a material carrying wing, indicated at 60. 70 This wing is secured to the outer end of the wing 12^a as by means of the hinge member 61 and vertical hinge pin 62^a and, as indicated, in operative position, extends forwardly in somewhat parallel relation to the 75 side of the car. As the car moves and the material accumulates forwardly against the wing 12^a this tends to displace the material carrying wing and in order to hold the same in desired position against such forces, I 80 provide a bracing strut or member 62 which extends between the forward end of wing 60 and the car.

The strut 62 is composed of two parts 62' and 62" pivotally joined by a hinge 85 having a horizontal pivot pin 63. It is pivoted to the car by means of a vertical pivot pin 64, and to the outer end of the material carrying wing 60, by means of a vertical pivot pin 65. The strut is further 90 braced by means of the diagonal angle frame 66 which has one end pivoted, by means of a vertical pivoted pin at the front lower end of the wing 60 as indicated at 67, and which has its other end secured to 95 the lower part of the brace portion 62". As the car moves forward, the ballasting or other material will engage the brace 66 and for this reason, I prefer to make it of an angle iron so positioned that the nose 66' 100 thereof points forwardly thus presenting a wedge shaped structure to the material well adapted for passage therethrough.

So soon as the material begins to accumulate between the wing 60 and the wing 12^a, 105 it is obvious that the wing 60 will be held in its outer position, but with my apparatus it is not necessary to depend upon the material to perform this function inasmuch as the wing is positively and powerfully held 110 in the proper position by means of the bracing structure just described. In order to assist in supporting the wing 60 especially when it is of considerable length, I prefer to provide a chain 68 which is anchored to 115 the vertical column 9 of the car, as indicated at 69, and to the outer end of the wing at 70. Such a chain while not essential assists in relieving the strain from the hinge parts.

A car provided with apparatus embodying my invention has the advantage of being operable entirely by workmen on the car there being no necessity of bracing or adjusting the parts from the ground, that 125 is after they have been initially assembled. It is clearly apparent from the drawings and description that the instant the wing

12^s is moved outwardly, by means of engine 19 that the wing 60 and bracing member 62 will be automatically distended into the proper operative position. Likewise when 5 the wing 12^s is retracted, the wing 60 and its braces are automatically collapsed or folded in to the proper position shown on the far side of the car in Fig. 1. It will also be understood that the entire wing structure, *i. e.* the wings 12^s and 60, may be raised or lowered from the car by operation of the engines 10. If the cut were a long one, the wings might be raised several times during the passage of the car through the cut 15 in order to place the accumulated ballast or other material in spaced piles within the cut for convenient removal later on.

While I have referred herein to ballast material, I wish it would be understood that 20 my apparatus may be used to advantage for other purposes one of which is the removal of snow.

Since this disclosure will readily suggest to others modified structures wherewith the 25 substantial objects and purposes of my invention may be attained, I do not wish to be limited to the specific structure herein shown and described, or to use with any particular type of railroad spreader or car 30 unless there be such limitations in the hereunto appended claims.

I claim:-

1. The improvements herein described comprising a car, in combination with a 35 side wing having its inner end pivoted thereto, a material carrying wing having its rear end pivoted to the side wing, means for swinging the side wing, and combined means for bracing the forward end of the 40 material carrying wing and for causing it to swing when the swinging movement is imparted to the side wing.

2. The improvements herein described comprising a car, in combination with a 45 side wing having its inner end pivoted thereto, a material carrying wing having one end pivotally joined to the side wing, wing swinging and holding braces joining the side wing and the car, means for actuating 50 said braces to swing the side wing, and wing swinging and holding braces joining the material carrying wing and the car whereby movement of the side wing causes movement of the material carrying wing.

55 3. The improvements herein described comprising a car, in combination with a side wing having its inner end pivoted thereto, a material carrying wing having its rear end pivoted to the side wing, means for 60 simultaneously swinging said wings, and means extending from the car to the forward end of the material carrying wing and forming a support therefor.

4. The improvements herein described

comprising a car in combination with a side 65 wing having its inner end pivoted thereto, a material carrying wing having its rear end pivoted to the side wing and a bracing member extending between the forward end of the material carrying wing and the car, 70 said brace being formed of pivotally united sections.

5. The improvements herein described comprising a car, in combination with a side wing having its inner end pivoted 75 thereto, a material carrying wing having its rear end pivoted to the side wing, a bracing member extending between the forward end of the material carrying wing and the car, 80 said brace being formed of pivotally united sections, one of the sections of the brace being relatively short, and a bracing strut extending diagonally from the short section to the material carrying wing.

6. The improvements herein described 85 comprising a car, in combination with a side wing having its inner end pivoted thereto, a material carrying wing having its rear end pivoted to the side wing, and a 90 bracing member extending between the forward end of the material carrying wing and the car, said brace being formed of pivotally united sections, one section being relatively short, and a bracing strut extending diagonally from the short brace member to 95 the material carrying wing, said diagonal brace being of wedge-like form presenting, when the wings are in operating position, its nose forwardly as and for the purpose specified.

7. The improvements herein described comprising a car, in combination with a side wing having its inner end pivoted thereto, a material carrying wing having its rear end pivoted to the side wing and a 105 bracing member extending between the material carrying wing and the car one end of said brace being pivotally joined to the car and the other end pivotally joined to the material carrying wing.

8. The improvements herein described comprising a car, in combination with a side wing having its inner end pivoted thereto, a material carrying wing having its rear end pivoted to the side wing and a bracing 115 member extending between the material carrying wing and the car one end of said brace being pivotally joined to the car and the other end pivotally joined to the material carrying wing, said brace being formed 120 of two parts united by a horizontally disposed pivot member.

9. The improvements herein described comprising a car, in combination with a side wing provided with a ditch forming portion adjacent its outer end and having its inner end pivoted to the car, a material carrying wing having its rear end pivoted to

the side wing outwardly of the ditch forming portion, and means for swinging said wings from the car.

10. The improvements herein described comprising a car, in combination with a side wing provided with a ditch forming portion adjacent its outer end and having its inner end pivoted to the car, a material carrying wing having its rear end pivoted to 10 the side wing outwardly of the ditch form-

ing portion, and means for simultaneously operating said wings from the car.

In testimony whereof I have hereunto set my hand, this 16th day of August, 1918, in the presence of two subscribing witnesses. 15

ROBERT E. BRESSLER.
